UNITED STATES PATENT OFFICE.

JAMES A. SEEING, OF CLEVELAND, OHIO, ASSIGNOR, BY MESNE ASSIGNMENTS, TO THE BISHOP & BABCOCK MANUFACTURING COMPANY, OF CLEVELAND, OHIO, A CORPORATION OF OHIO.

TELESCOPING CABINET COVER.

Application filed February 3, 1925. Serial No. 6,537.

The present invention relates to tops for soda fountain cabinets and the like. The present top construction is of the sliding type so as to cover a cabinet with two compartments and is so arranged as to present a substantially flush upper surface and to overlap the cabinet top on all sides.

The cover is so constructed that one half is adapted to slide into the other, and each half is movable so as to allow easy entrance to either side of the cabinet. The entire cover is readily removable and leaves the cabinet top wide open for filling or cleaning.

To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Fig. 1 is a top plan view of a cabinet showing the cover in place in its extended position; Fig. 2 is a vertical longitudinal section on the line 2—2 of Fig. 1; Figs. 3, 4 and 5 are sectional views of details taken on the lines 3—3, 4—4, and 5—5 respectively of Fig. 1; and Fig. 6 is a sectional view similar to Fig. 3 but showing the cover applied to a modified form of cabinet construction.

The present cover is adapted to be used on soda fountain cabinets of the usual type comprising a rectangular structure having side walls 1 and end walls 2 of considerable thickness and properly insulated and have rather wide upper surfaces 3. The cabinet may be divided into two separate compartments by a center partition or may be left as a single compartment as shown.

The cover consists of a box or casing formed of suitable sheet metal of non-rusting material, this box having a bottom portion 6 filled with insulating material 7 and a pocket 8. Near the upper edge, the side walls 9 are bent out as at 10 and then up as at 11 to form a flange 12 around three sides of the cover and guideways 13 at the top of the pocket. The top 14 of the box has its forward edge turned up and rebent along itself to form a stiffening flange 15 to prevent buckling or bending.

The other cover portion consists of a box 20 of sheet metal filled with insulating material and provided with a flange 21 around three sides, this flange 21 being of a thickness to fit within the guideways 13 so that this cover half 20 may telescope in the cover half 5. Each cover half is provided with a knob or handle 25 for ease in handling and moving. The flanges 21 of the telescoping cover half 20 are wide enough to overlap the upper surfaces 3 of the cabinet walls as best shown in Fig. 1 and the upper surfaces of the two cover halves are substantially level, the difference in height being only the thickness of the top 14 of the cover half 5.

To aid in holding the cover half 20 in its closed position, it is provided on its lower edge with a locking clip 30 of angle section, which is adapted to engage over a complementary clip 31 secured to the cabinet wall. To release the clips, it is only necessary to raise the cover half 20 slightly which is the normal action in grasping its handle, after which the half 20 may be telescoped into the half 5 to open the right hand half of the cabinet.

The cover halves fit the cabinet fairly snugly, the half 5 fitting rather tightly as shown in Fig. 3 while the half 20 is looser as shown in Fig. 4 to allow for its own movement into the half 5 where it fits so as to just be easily movable as best shown in Fig. 5.

In Fig. 6, the same covers are shown as applied to a modified form of cabinet construction in which an angle iron 40 is mounted along the inner edges of the cabinet to provide a raised flange or shoulder 41 thereon to prevent spilled liquid from dripping into the cabinet compartment.

The present type of sliding cover may be removed as a telescoped unit of half size thus taking up a minimum space. It is easily moved to telescope in either direction so as to open either half of the cabinet and it provides a substantially flush upper surface above the level of the top of the cabinet. It allows the interior walls of the cabinet to be kept free of shoulders or guideways for the covers. As the cover overlaps the entire four walls of the cabinet, it completely closes the same and anything dropping or spilling on the cover halves may be readily wiped off without danger of forcing it into the cabinet proper.

Both cover halves are properly insulated,

each being provided with a heavy insulated bottom portion. The covers are inexpensive in construction as they may be made of sheet metal sections which can be welded together 5 so as to present watertight boxes if desired. The rebent edge of the pocket stiffens the top so that the top is not easily bent, thus reducing the pocket size or binding the two covers together.

10 Other modes of applying the principle of my invention may be employed instead of the one explained, change being made as regards the mechanism herein disclosed, provided the means stated by any of the following claims 15 or the equivalent of such stated means be employed.

I therefore particularly point out and distinctly claim as my invention:—

1. In a sliding top for cabinets, the combination of a half cover provided with an insulated box at the bottom, the sides of said cover being extended upwardly from said box and then outwardly and upwardly to form a flanged pocket above said box, a top 25 for said half cover rigidly secured to said sides, and a second half cover comprising an insulated box slightly narrower than said first half cover and provided near its top with laterally projecting flanges, said second 30 half cover being adapted to telescope into said first half cover with its flanges in the pocket flanges, said two half covers being adapted in their extended position to have their flanges rest on the cabinet top and overlap 35 the compartment opening on every side so as to completely close the compartment.

2. In a sliding top for cabinets, the combination of a half cover provided with an insulated box at the bottom, the sides of said 40 cover being extended upwardly from said box and then outwardly and upwardly to form a flanged pocket above said box, a top for said half cover rigidly secured to said

sides, and a second half cover comprising an insulated box slightly narrower than said 45 first half cover and provided near its top with laterally projecting flanges, said second cover half being adapted to telescope into said first half cover with its flanges in the pocket flanges, said two half covers being adapted 50 in their extended position to have their flanges rest on the cabinet top and overlap the compartment opening on every side so as to completely close the compartment, a handle mounted on each cover half, the 55 handle on said telescoping second half cover being so positioned as to limit the telescoping movement.

3. In a sliding top for cabinets, the combination of a half cover provided with an insulated box at the bottom, the sides of said cover being extended upwardly from said box and then outwardly and upwardly to form a flanged pocket above said box, a top 60 for said half cover rigidly secured to said sides, the forward edge of the top being turned upwardly and rebent on itself to form a stiffening flange across the mouth of the pocket, and a second half cover comprising an insulated box slightly narrower than said 65 first half cover and provided near its top with laterally projecting flanges, said second cover half being adapted to telescope into said first half cover with its flanges in the pocket flanges, said two half covers being 70 adapted in their extended position to have their flanges rest on the cabinet top and overlap the compartment opening on every side so as to completely close the compartment, a handle mounted on each half cover, the 75 handle on said telescoping second half cover being so positioned as to limit the telescoping movement.

Signed by me this 29 day of January, 1925.

JAMES A. SEBRING.
